UNITED STATES PATENT OFFICE

ALONZO LINTON BAUSMAN, OF SPRINGFIELD, MASSACHUSETTS

COLLAR AND CUFF IRONING MACHINE

Application filed September 13, 1929. Serial No. 392,363.

This invention relates to improvements in collar and cuff presses for laundry use. One object of the invention is to construct a press adapted to this purpose in which there is improved equalization of pressure on the several collar and cuff bucks. A further object is to improve presses of this type in the matter of securing exact registration of the several upper and lower pressing members. A further object is to provide a press in which the positioning of the work on the several bucks will be facilitated, and in which the operator will not be required to move from her normal position in turning from one buck to another.

The press in which the invention has been embodied will be described in connection with the accompanying drawings, in which:

Fig. 1 is a side elevation;

Fig. 2 is a top plan view of the upper press head, taken on line 2—2 of Fig. 1;

Fig. 3 is a front elevation of the upper and lower press heads, taken substantially on line 3—3 of Fig. 2 and for purposes of clarity showing the heads as if the angular arrangement illustrated in Fig. 2 were not present;

Fig. 4 is a section on line 4—4 of Fig. 3; and

Fig. 5 is a section on line 5—5 of Fig. 3.

The press is carried upon a frame 10, to which is pivoted at 11 an upper head carrying arm or yoke 12. The arm has a rearward extension 13, to which an adjustable link 14 is pivoted at 15, the other end of the link being pivoted at 16 to a second link 17. At its lower end this second link is swingingly mounted on the frame at 18, and forms together with link 14 a toggle, the straightening of which causes the press to be closed. Pivoted to the link 17 at 19 is the piston rod of a pneumatic cylinder 20, the action of which may be controlled by any suitable valve mechanism. The counterweight 21 is pivoted to the frame and is joined to arm 13

by a link 22. The details of the press operating mechanism as described above do not form part of my present invention, and are described only to complete the disclosure of an operative mechanism.

Threaded into a boss 23 formed in the center of the forward portion of the arm 12 is a ball pointed screw 24 held in adjusted position by a lock nut 25. The ball end of this screw fits into a cup-shaped depression 26 in an equalizing bar 27 curved as shown in Fig. 2 for a purpose to be described. In Fig. 3 the curve has been eliminated in order to show the parts without introducing a confusing perspective. Studs 28, preferably four in number, are secured to the equalizing bar and extend upwardly through holes in a flange 29 formed as a part of arm 12. Above the flange, springs 30 are mounted upon the studs and are surmounted by washers 31 and nuts 32 so that their tension may be adjusted individually. The arrangement described permits a slight rocking movement of the equalizing bar with the ball pointed screw 24 as a pivot, a normal position of the bar parallel to the flange 29 being maintained yieldably by the springs 30.

At a generally central position a smaller ball pointed screw 35 is threaded through the equalizing bar and is held in adjusted position by a lock nut 36. The ball end of this screw fits into a cup-shaped depression 37 in an upper collar press head 38, cored at 39 and fitted with pipes 40 for the circulation of steam. Studs 41 on the press head, preferably four in number pass upwardly through the equalizing bar, and are provided with springs 42, collars 43, and nuts 44. The collar press head is thus mounted so that it may have a slight yielding rocking motion around the ball end of the screw 35. At each end of the equalizing lever is a ball ended screw 45 held in adjusted position by a lock nut 46. The ball end of this screw fits into a cup-shaped depression 47 in an upper cuff-

pressing head 48, cored at 49 and provided with pipes 50 for the circulation of steam. Studs 51 on each cuff pressing head, preferably four in number, pass upwardly 5 through the equalizing bar, and are provided with springs 52, washers 53, and nuts 54. Each cuff press head is thus mounted for independent rocking movement in a yielding manner similarly to the collar press head.

10 The collar and cuff press heads have concave lower ironing surfaces 55 and 56, respectively.

Secured to the frame below the movable press heads is a buck base 60 having a cylindrical extension 61 fitting into a recess in the frame. A collar buck 62 is secured to the center of this base by bolts 63. Ways 64 (Fig. 1) are formed in the ends of the equalizing bar, and receive slidably a pair of cuff bucks 15 65 corresponding to the two cuff press heads carried upon the arm 12. Each cuff buck has a downwardly extending lug 66 which has threaded into it an adjusting screw 67 mounted for rotation in but held against longitudinal movement with respect to the buck base 20 60. The collar and cuff bucks have convex upper surfaces 68 and 69, respectively, adapted for the reception of the usual padding 85 which has not been shown on Fig. 1 as its illustration would obscure the holes 78.

The buck base is cored out as at 70 to provide a central steam passage by which it, and the air circulated through it as will be described, can be heated. On each side of the 35 steam passage are air passages 71 and 72 which open towards the machine frame in the cylindrical extension 61 and towards the several collar and cuff bucks each of which is cored out to provide air passages 73 and 40 74. A fan 75 is mounted in the machine frame, and is provided with a suction passage 76 and an exhaust passage 77 registering with the passages 71 and 72, respectively. The outer surface of each of the bucks is dotted 45 with small holes 78 extending into the air passages, about half of the holes in each buck connecting with the suction passage and the other half with the exhaust passage. The action of the fan will be to circulate air 50 through the bucks and through the padding mounted upon them. The air will pass out one set of holes, through the padding and back into the buck through the other set of holes. In some aspects of my invention, the 55 circulatory feature of the air supply could be dispensed with and the air blown or sucked directly through the padding, although the construction described is preferred.

It will be noted from the plan view of Fig. 60 2 that the two cuff pressing units are arranged at oblique angles with respect to the central collar pressing unit, this angular position being aided by the curvature of the equalizing bar. This arrangement greatly reduces 65 the movement required of the operator in

placing the work upon the press. From a permanent station indicated conventionally at 80, the operator may reach the three pressing units with only slight turning. Were the three units arranged in a line, a bodily shifting of the operator's position would be required.

Claims:

1. In a laundry press of the type having a stationary press head presenting a plurality of ironing surfaces and a movable press head carrying a plurality of ironing surfaces into coaction with the stationary ironing surfaces, that construction of the movable press head comprising a movable operating arm, an equalizing lever pivotally secured to the arm, and a plurality of ironing members each pivotally secured to the equalizing lever.

2. In a laundry press of the type having a stationary press head presenting a plurality of ironing surfaces and a movable press head carrying a plurality of ironing surfaces movable into coaction with the stationary ironing surfaces, that construction of the movable press head comprising a movable operating arm, an equalizing lever pivotally secured to the arm, a plurality of ironing members each pivotally secured to the equalizing lever, and a spring device associated with each of the ironing members and operative to maintain the members in normally centralized position.

3. A laundry press comprising a stationary press head presenting a plurality of padded ironing members, a single movable press head carrying a plurality of separate ironing members and movable to bring said members into coaction with the padded ironing members on the stationary press head, separate supply and return air passages in the stationary press head, said passages being common to all of the stationary ironing members, separate supply and return air passages in each of the stationary ironing members connecting with the common passages in the press head, two sets of perforations in each stationary ironing member connecting both of the air passages therein with the padding surrounding the member, and means connected with the common supply and return air passages in the stationary head for circulating air through them.

4. A laundry press comprising a lower buck, a central ironing member mounted on the buck, a pair of end ironing members separately adjustable towards and away from the central member, an upper head, an equalizing member carried by the head, and a central and a pair of end ironing members carried by the equalizing member and each yieldably pivotally mounted thereon for coaction with the ironing members carried by the lower buck.

5. A collar and cuff ironing press comprising a stationary jaw presenting a central con-

convex collar ironing surface and a pair of convex cuff ironing surfaces disposed at angles to and projecting in front of the collar ironing surface so that they can readily be reached by an operator standing directly in front of the collar ironing surface, a movable jaw carrying ironing members shaped to conform to the ironing surfaces of the stationary jaw and arranged similarly thereto, and means for moving the movable jaw to bring the ironing surfaces in unison against the stationary ironing members.

In testimony whereof I have affixed my signature.
